UNITED STATES PATENT OFFICE

152,236

DESIGN FOR A BRACELET OR THE LIKE

Karl C. Augenstein, Cranston, R. I., assignor to
Speidel Corporation, Providence, R. I., a cor-
poration of Rhode Island

Application June 9, 1948, Serial No. 146,861

Term of patent 14 years

(Cl. D45—4)

To all whom it may concern:

Be it known that I, Karl C. Augenstein, a citizen of the United States of America, residing at Cranston, county of Providence, and State of Rhode Island, have invented a new, original, and ornamental Design for Bracelet or the like, of which the following is a specification, reference being had to the accompanying drawing, forming a part thereof.

Fig. 1 is a top plan view of a bracelet embodying my new design with the links contracted and a portion thereof broken away for illustrative purposes;

Fig. 2 is a view similar to Fig. 1 with the links in an expanded position; and

Fig. 3 is a side elevational view of the link portion of the bracelet as shown in Fig. 1.

The dominant features of my design reside in the portions shown in full lines.

I claim:

The ornamental design for a bracelet or the like, substantially as shown and described.

KARL C. AUGENSTEIN.
